UNITED STATES PATENT OFFICE.

JOSEPH DEL COZZO, OF SCOTIA, AND ALBERT W. GOBLE, OF FORTUNA, CALIFORNIA.

SIGNALING DEVICE.

Application filed January 16, 1925. Serial No. 2,915.

To all whom it may concern:

Be it known that we, JOSEPH DEL COZZO and ALBERT W. GOBLE, a subject of the King of Italy and a citizen of the United States, 5 resp., residing at Scotia and Fortuna, resp., in the county of Humboldt and State of California, have invented new and useful Improvements in Signaling Devices, of which the following is a specification.

10. This invention relates to improvements in signaling devices and has particular reference to means for signaling when the cooling fluid of an internal combustion engine reaches a low point in the radiator, 15 where it would be dangerous to run further without replenishing the water.

Another object of this invention is to produce a device of this character which may be attached to any automobile, without 20 altering the construction of the same.

An additional object of this invention is to produce a device of this character which is simple in construction, cheap to manufacture and one which is relatively 25 free from complicated parts which might be easily deranged.

A still further object of this invention is to provide means whereby the escape 30 of fluid is prevented until the fluid has reached a point beneath the inlet of our device.

Other objects and advantages will be apparent during the course of the following description.

35. In the accompanying drawings forming a part of this specification, and in which like numerals are employed to designate like parts throughout the same,

40. Figure 1 is a side elevation of our device, shown attached to an automobile radiator and to the instrument board thereof,

Figure 2 is an enlarged detail cross section showing the valve arrangement,

45. Figure 3 is a vertical cross section showing one of the whistles located adjacent to the instrument board,

Figure 4 is a detail view of the sliding pipe connection, and

50. Figure 5 is a modified form of our device showing the auxiliary whistle attached to the top of the radiator.

In automobiles, it is common to have the water evaporate from the cooling system and in hot weather this evaporation is exceedingly rapid, with a result that often 55 the water reaches a boiling point and after

the evaporation has taken place to a considerable extent, the engine is apt to overheat and become injured. We have, therefore, devised a means whereby when the 60 water in the radiator evaporates to a predetermined point an audible signal will be given.

In the accompanying drawings wherein for the purpose of illustration is shown 65 a preferred embodiment of our invention, the numeral 5 designates the ordinary radiator of an automobile and 6 the instrument board, common in many makes of automobiles.

The numeral 7 represents the dash. Secured in one side of the radiator, at a point just within the usual hood, we secure a casting 8, it being immaterial whether this casting is connected at this exact point or not, 75 as long as it has communication with the interior of the radiator, at a point beneath the safety water line.

By referring to Figure 2, it will be noted that this casting has a tubular projection 9, which is screw-threaded so as to engage the radiator 5. A screen 11 serves to exclude foreign matter from entering the signaling device. This casting has formed therein a chamber 12 within which a ball 80 float 13 is positioned and adapted to close the bore 14, as will be later described.

This ball 13 is prevented from dropping beyond a predetermined point by a pin 16. A second ball valve 17 closes the opposite 90 end of the bore 14 and is held in contact therewith by a spring 18. This spring bears upon the under surface of a whistle 19.

At 21 we have shown a pipe extending 95 from the casting 8 and communicating with the bore 14, which pipe may be connected to a slip pipe 22, from which slip pipe, a pipe 23 extends to a slip joint 24, from which slip joint a pipe 26 extends to a whistle 27. This whistle is secured to a 100 housing 28, which is, in turn, fastened to the instrument board 6, as by bolts 29 and 31. The slip joints 22 and 24 may be constructed as shown in Figure 4, thus providing for the lengthening or shortening 105 of the pipe, as necessity demands.

A packing is shown at 32 which is tightened by a nut 33.

The operation of our device is as follows:

Assuming that the parts are attached to an automobile and that the water level in

the radiator is sufficient to cover the end of the tubular projection 9, the result will be that water will enter the chamber 12 and raise the float 13 into engagement with its seat, thus preventing the escape of the water to the bore 14. This condition will be maintained at all times, when the radiator is full.

When the water in the radiator has evaporated to a point beneath the end of the tubular member, steam will enter the chamber 12, the ball 13 will have dropped against its pin 14, thus permitting the steam to pass through the pipe 21, to pipe 23, to pipe 26, to whistle 27 and as this whistle is mounted close to the driver, he will immediately be warned that more water should be placed in the radiator.

The escaping steam will condense in the housing 28 and escape through the opening 34. Should the pipe for any reason, become clogged, the pressure then would lift the valve 17 against the tension of the spring 18, which will permit the steam to operate the whistle 19, which is of a different tone than the whistle 27 and should be shrill so as to warn the driver.

In the modified form shown in Figure 4, a pipe 35 is attached to the top of the radiator which pipe is, in turn, connected to the T 36 from which the auxiliary whistle, similar to that shown at 21, in Figure 1, is suspended. The T 36 is also connected to the pipe 23.

It will thus be seen that we have provided a very simple device and one which will effectively warn the driver when the water condition demands attention.

It is to be understood that the form of

our invention herewith shown and described is to be taken as a preferred example of the same, and that various changes in the shape, size and arrangement of parts may be resorted to without departing from the spirit of the invention or the scope of the subjoined claim.

Having thus described our invention, we claim:—

In a device of the character described, the combination with a radiator for an internal combustion engine, of a casting having a tubular portion secured to said radiator at a point below the normal water-line of said radiator and communicating with the interior thereof, a chamber formed in said casting, a buoyant ball positioned in said chamber, a bore formed in said casting and adapted to be closed at one end by said buoyant ball when said chamber is filled with water from said radiator, a second ball adapted to close the opposite end of said bore from that closed by said first mentioned ball, spring means for retaining said second mentioned ball in closed position, an auxiliary whistle secured to said casting at a point adjacent said second mentioned ball and in such a manner that said second mentioned ball will be positioned between said bore and said whistle, a whistle remotely located with respect to said casting, and a pipe for conducting pressure from said bore to said last mentioned whistle.

In testimony whereof we affix our signatures.

JOSEPH DEL COZZO.
ALBERT W. GOBLE.
